CONTAINER CLOSURE

Charles H. Rasmussen, Brooklyn, N. Y., assignor
to Ferdinand Gutmann & Co., Brooklyn, N. Y.,
a corporation of New York

Application September 25, 1935, Serial No. 41,963

7 Claims. (Cl. 215—43)

The invention relates to container closures, and more particularly to what is known as a "double shell" screw cap of a type having an outer metallic shell provided with a smooth skirt and an inner metallic shell having a screw threaded skirt.

Double shell closures of the type to which the invention relates are used in very large quantities. Such closures not only have an attractive finish and are capable of having lithographic decorations impressed thereon, but the screw threads of the inner shell are not subject to distortion or deformation while a closure is being applied by a machine to a bottle.

Heretofore, in the production of such closures, great difficulty has been experienced in securing a sufficiently tight joinder of the inner and the outer shells to avoid the production of closures in which there will not be an objectionably high percentage of closures defective in the respect that, when attempting to remove a closure, the connection between the two shells will be loosened to an extent to permit the free turning of the outer shell about the inner shell. This condition is greatly exaggerated if there be a slight deformation of the outer shell due to the handling of closures by an applying machine. A defective joint between the two shells may result from variance in the thickness of the metal in different closures, or a failure of the tools used in assembling the closure to develop in all closures, the same pressure relation between the inner and the outer shells.

To correct this condition, there has been developed a closure in which the inner shell has an interrupted, outwardly flared bottom flange which, as a result of the rolling or turning of the bottom of the outer shell, has its edge forced outwardly so as to engage and bite into the inner wall of the skirt of the outer shell. The depth of this bite cannot be great without forcing the metal of the skirt outwardly, forming irregularities in the outside of the skirt of the outer shell. With this type of closure, the application of excessive force in an effort to turn the closure may cause cutting of the material of the skirt of the outer shell to an extent to permit said shell to turn independently of the inner shell.

In other forms of this type of closure, the skirt of the inner shell is clamped against the skirt of the outer shell by the rolled edge of the latter. Neither of these practices, however, has proven entirely satisfactory in use because such closures are made by automatic machinery, and an adequate inspection of the completed product

is impossible since the defects resulting in a free turning of the outer shell are developed only when it is attempted to remove the closure from, or apply it to, a container.

In the production of double shell closures prior to my invention, the turning or rolling of the edge of the skirt of the outer shell developed stresses upon the skirt of the inner shell lengthwise thereof which had a tendency to deform the screw threads formed in this skirt, thus interfering with a proper attachment and removal of the closure from the neck of a bottle or other container. The rolled threads upon the skirt of the inner shell reduce the resistance to such stresses, the drawn portions of the metal weakening the skirt throughout the threaded portion thereof and permitting the partial collapsing of this threaded portion with the application of comparatively light pressure thereto.

With the above conditions in mind, I have produced a double shell container closure wherein frictional engagement between the rolled edge of the skirt of the outer shell and the skirt of the inner shell is not relied upon to prevent relative movement of these shells, but wherein the tensile strength of the rolled portion of the outer shell is utilized for this purpose. With this construction, the turning of the outer shell independently of the inner shell is possible only as a result of excessive distortion of the bead or roll of the outer shell, the possibility of which is remote since this portion of the shell is greatly stiffened by the bead or roll.

While, in the production of the closure, there is a clamping action of the roll or bead of the outer shell upon short, spaced areas of the inner shell, this is not relied upon to effectively connect the two shells, being merely incidental to the methods employed in permanently uniting the two shells.

In a container closure embodying the invention, the turning of the outer shell in relation to the inner shell is resisted by the bead or roll of the outer shell which abuts opposite edges of widely spaced lugs about the edge of the inner shell.

In the production of a closure embodying the invention, I preferably so form the outer shell as to accurately center the inner shell in relation thereto during the assembling operation, the means for so centering said inner shell also serving to space the screw threaded skirt of the inner shell from the skirt of the outer shell sufficiently to permit a limited degree of flexure of this skirt in adapting itself to the screw threads upon a bottle or other container. Such means also serve

as a handhold to facilitate the removal of the closure from a container, but are not essential to the invention since the construction of the inner shell may be so modified as to secure the desired centering thereof in the outer shell.

The invention consists primarily in a container closure embodying therein an outer shell having a skirt, and an inner shell having a skirt provided with means adapted to co-operate with complementary means upon the neck of a container in applying a closure to, or removing it from, a container, the bottom edge of the skirt of said inner shell being provided with a plurality of pendant lugs spaced in relation to each other circumferentially of the skirt, and the bottom edge of the skirt of said outer shell being inwardly curled to bring its edge in abutting relation to the skirt of the outer shell intermediate said lugs and in engaging relation with the opposite edges of each 20 of said lugs; and in such other novel features of construction and combination of parts as are hereinafter set forth and described, and more particularly pointed out in the claims hereto appended.

Referring to the drawing,

Fig. 1 is a side view, broken away upon different vertical planes, to disclose the construction and relation of parts in a fully assembled cap;

Fig. 2 is a side view of the inner shell;

Fig. 3 is a view, partly in section, of the outer shell prior to the assembly of the closure; and

Fig. 4 is a horizontal section upon an enlarged scale of one of the lugs of the inner shell immediately above the curl of the outer shell.

Like numerals refer to like parts throughout the several views.

In the accompanying drawing, the closure is shown upon an enlarged scale, and the thickness of the material of which the two shells are formed is exaggerated. In a closure embodying the invention, I employ an outer shell 10 having a closed top 11, which may be domed as shown in the drawing, and a skirt 12. Nested within the skirt 12 is an inner shell 13 having a skirt 14 provided with screw threads 15 or other means adapted to cooperate with complementary means about the neck of the container in applying the closure to, or removing it from, a container.

The skirt 14 of the inner shell 13 is provided with an outwardly extending bottom flange 16 adapted to have a loose fit with the inner wall of the skirt 12 of the outer shell considerably above the bottom of said skirt. This flange tends to stiffen the bottom of the skirt 14 and aids in centering the inner shell in relation to the outer shell.

Projecting downwardly from the edge of the flange 16 is a plurality of lugs 17, utilized in securing the inner and outer shells together in a manner to be hereinafter referred to. Said lugs preferably have a curved edge circumferentially of the edge of the skirt, as indicated at 18, and have the same circumferential curvature as the skirts 12 and 14. By locating these pendant lugs 17 at the outer edge of the flange 16, they are brought into close abutting relation with the skirt 12 of the outer shell 10. The lugs 17 are of a height to position the ends thereof sufficiently above the bottom edge of the skirt 12 of the outer shell to allow the portion of said skirt adjacent said edge to be curled or rolled inwardly and upwardly in a manner to locate the curl in its entirety below and in substantial engagement with the bottom of the radial flange 16. When curling 75 the edge portion of the skirt 12, the bottom edge

of the metal of the skirt is brought into substantial engagement with the inner face of the skirt 12, as indicated at 19, the remaining portions of said edge being engaged with the several lugs 17.

When rolling or curling the material of the skirt 12, movement of that portion thereof engaging the lugs 17 is arrested before the curling action is completed, thus causing deformation or distortion of the portion of the skirt 12 which engages the lugs in a manner to form shoulders 20 upon the curled or rolled portion 21 of the outer skirt adjacent and in abutting relation to opposite edges of each lug. Such shoulders have dimensions substantially equaling the thickness of the metal of the lugs and, by reason of conditions well known to sheet metal workers, these shoulders will not be abrupt but will be slightly bevelled. This condition is merely an unavoidable condition in sheet metal work.

By the above construction, pockets for the reception of the various lugs 17 are formed in the curl or roll during the assembling of the closure, the portions of the curl or roll forming the edges of each pocket constituting a barrier to restrain relative turning movement of the two shells either during the application of the closure to, or its removal from, a container.

The shoulders 20 can only be of a width corresponding with the thickness of the material of the lugs. In order to increase their effectiveness, I provide lugs having a curved edge, which, as shown in Fig. 4, during the deformation of the material of the curl, roll or bead 21, will give increased length to these shoulders so as to increase the contacting area between the curl, roll or bead 21 and the lugs 17.

With the construction shown and described, the several lugs 17 are confined in substantially their entirety within the curl, roll or bead 21 about the edge of the closure, but the height of these lugs is such that they are not turned with the edge of the skirt 12 of the outer shell when forming the curl, roll or bead. Any curling of the lugs, however, would have no useful purpose in the closure. If, however, the lugs should be too high or the curling tools should not act properly as to all closures, these lugs may be distorted without any modification of the structure of the completed cap.

The radially extending flange 16 from which the lugs 17 depend, serves to offset the lugs in relation to the screw threaded portion of the skirt, so as to bring them into a close sliding fit with the inner wall of the skirt 12 of the outer shell 10, thus serving the two-fold function of bringing said lugs within the desired operative position in relation to the curl, roll or bead 21, and of providing clearance between the screw threaded portion of the skirt 14 and the skirt 12 of the outer shell sufficient to permit flexure of the screw threads in adapting themselves to the screw threads about the neck of a container. This flange also stiffens the lower portion of the skirt 14 and centers this portion of the skirt in relation to the skirt 12 of the outer shell, the lugs 17 contributing toward securing the desired relative positioning of the two shells during the assembling operation.

During the formation of the curl, roll or bead 21, the pressures developed under normal conditions are radially of the closure and against the skirt 12 of the outer shell, thus relieving the screw threaded skirt 14 of the inner shell from any stresses tending to close or partially collapse 75

the screw threads. In the event of irregularities in the co-operating shells of different closures, the curl, roll or bead 21 may, while it is being formed, engage the bottom face of the flange 16. The material of the inner shell being of thin gauge sheet metal, any pressure upon this flange toward the top of the inner shell will merely result in the yielding of the flange 16 without developing stresses upon the skirt 14 sufficient to cause any deformation of the screw threaded portion thereof.

The form of the closed tops of the inner and outer shells is largely a matter of selection, it being merely necessary that the top of the inner shell shall engage that of the outer shell in order to facilitate the assembling of the two shells and ensure a continued fixed relative position of these shells.

Ordinarily, a portion of the skirt 14 adjacent the top of the inner shell is of relatively greater diameter, as shown at 22, than the screw threaded portion of the skirt so as to permit a cushion disk or liner 23 to be inserted and held within said inner shell adjacent the top thereof.

While the flange 16 serves to center the inner shell 13 in relation to the outer shell during the assembling of the two shells, I prefer to provide the skirt 12 of the outer shell with a plurality of spaced depressions 24, these depressions being of a depth to lightly engage the enlarged portion 22 of the inner shell and assist in centering the inner shell in relation to the outer shell during the assembling operation. These depressions 24 also serve as handholds to facilitate the removal of a closure from a container, such closures ordinarily being applied to a container by a canning machine.

The manner of assembling and the operation of a closure embodying the invention is substantially as follows:—

In the production of closures embodying the invention, the outer shell 10 is drawn from sheet metal to substantially the form shown in Fig. 3 of the drawing. The inner shell 13 is also drawn from sheet metal, and the screw threads or other attaching means formed therein to produce an inner shell of the form shown in Fig. 2. The sheet metal of which outer shells 10 are formed may be decorated in any desired manner prior to the feeding of the sheet to a punch press for forming the shell.

A previously formed inner shell is then inserted in a previously formed outer shell, the flange 16 serving to center the two shells in relation to each other, the depressions 24 in the skirt of the outer shell, by engagement with the enlarged portion 22, assisting in the centering of the two shells.

When the two shells are thus positioned, the screw threaded portion 15 of the skirt is spaced from the skirt 14 of the outer shell, and the lugs 17 are in contact with the skirt 14 adjacent its lower edge, the flange 16 extending radially of the inner shell from said lugs to the screw threaded portion of the skirt.

When I refer to the bottom of the shells 10 or 13, I have reference to the free edge of the skirts thereof.

After the nesting of the inner shell in the outer shell in the manner described, the bottom edge of the skirt 14 is curled or rolled in a manner well known in the production of container closures to form the curl, roll or bead 21. During the curling or rolling operation, which is inwardly of the closure, the edge of the skirt 14, before the completion of said operation, engages the inner face of several lugs 17. This contact of the edge of

the skirt of the outer shell with said lugs forces the lugs into intimate contact with the inner wall of the skirt 14 and develops a strong frictional contact between the curl, roll or bead 21 and said lugs. The engagement of the edge of the skirt 14 with the lugs 17 is primarily for the purpose of causing the formation of the shoulders 20, since the portion of the curl engaging the lugs 17 will be slightly deformed, and the portions of the curl upon each side of the lug will be forced past the lug into engagement or substantial engagement with both edges of the lug and with the inner wall of the skirt 14.

The extent of deformation of that portion of the material of the skirt 14 engaging the lugs 17, is determined by the contour of said lugs, so that with a curvature of the edge of the lugs as described, the length of the shoulders 20 will be relatively greater than with an angular or other form of lug.

In a closure formed in the manner described, the inner shell is held against rotative movement, in relation to the outer shell, by the confining of a plurality of lugs 17 within shouldered pockets formed in the curled, rolled or beaded portion of the outer skirt.

The curl, roll or bead 21 of the outer skirt serves to very materially stiffen the bottom edge of the skirt 14, and with the lugs confined in the manner described, it is impossible to turn the outer shell in relation to the inner shell without spreading a considerable length of the curl, roll or bead. Ordinarily the curl, roll or bead is sufficiently rigid to resist sufficient distortion thereof to allow turning of the outer shell in relation to the inner shell.

In forming the curl, roll or bead, it is given a circular form and has a trend toward the bottom of the closure prior to its engagement with the lugs 17. Consequently, the shoulders 20 result from the closing of the edge portion of the curl, roll or bead engaging said lugs. The portions of the curl, roll or bead intermediate the lugs are forced past the lugs without the more abrupt curvature present at the lugs. Consequently, the outer shell can have no movement in relation to the lugs unless pressures are developed great enough to cause additional turning of the edge of the skirt 14 embodying the curl, roll or bead, since the thickness of the material of the lugs is sufficiently great to preclude any possibility of their being forced between the curl, roll or bead and the portion of the skirt 14 with which it contacts.

In a closure embodying the invention, the curl, roll or bead 21 effectively stiffens the lower edge of the closure, and as to the parts thereof between the lugs 17, effectively resists any relative turning movement of the two shells, since a shoulder 20 abuts against each edge of each lug. While each lug is clamped between the portion of the bead engaging same and the adjacent portion of the skirt, this is not relied upon to prevent relative movement of the two shells, and alone would prove ineffective for this purpose. If the closure were made without this feature, the relative movement of the two shells would still be impossible.

In the form of the invention shown in the drawing, three lugs 17 are employed, said lugs being spaced apart approximately 120° in arc. This construction has been found effective in securing a desired permanency in the union of the two shells. The exact number and spacing

of said lugs, however, is immaterial to the invention.

The shoulders 20 are formed by a drawing of the metal across the opposite edges of each lug 17 when closing the curl, roll or bead. By using a lug having a curved edge, this drawing action is less difficult and the length of the shoulder is increased.

The essential characteristics of the invention 10 are the inner shell with its pendant lugs, and the outer shell with its curled, rolled or beaded lower edge embracing said lugs and formed about the edges thereof in a manner to produce shoulders as herein described.

15 It is not my intention to limit the invention to the precise details of construction shown in the drawing, it being obvious that such may be varied without departing from the spirit and scope of the invention.

20 Having described the invention, what I claim as new and desire to have protected by Letters Patent, is:—

1. A container closure embodying therein an outer shell having a skirt, and an inner shell 25 having a skirt provided with means adapted to co-operate with complementary means upon the neck of a container in applying a closure to, or removing it from, a container, the bottom edge of the skirt of said inner shell being provided 30 with a plurality of pendant lugs spaced in relation to each other circumferentially of the skirt, and the bottom edge of the skirt of said outer shell being inwardly curled to bring its edge in abutting relation to the skirt of the outer shell 35 intermediate said lugs and in engaging relation with the opposite edges of each of said lugs.

2. A container closure embodying therein an outer shell having a skirt, and an inner shell having a skirt provided with means adapted to co-operate with complementary means upon the neck 40 of a container in applying a closure to, or removing it from, a container, the bottom edge of the skirt of said inner shell being provided with a plurality of pendant lugs spaced in relation to each other circumferentially of the skirt, and the bottom edge of the skirt of said outer shell being provided with a continuous, uninterrupted inwardly and upwardly curled portion 45 with its edge in abutting relation to the skirt of the outer shell intermediate said lugs and with the inner face, and in engaging relation with the opposite edges of each of said lugs.

3. A container closure embodying therein an outer shell having a skirt, and an inner shell having a skirt provided with means adapted to co-operate with complementary means upon the neck 55 of a container in applying a closure to, or removing it from, a container, the bottom edge of the skirt of said inner shell being provided with an outwardly directed flange of a width to engage the skirt of said outer shell, and having at the outer edge thereof a plurality of pendant lugs spaced in relation to each other circumferentially of the skirt, and the bottom edge of the skirt of said outer shell being inwardly curled to bring its edge in abutting relation to the skirt of the outer shell 65 intermediate said lugs and in engaging relation with the opposite edges of each of said lugs, and the upper portion thereof in engagement with said flange.

4. A container closure embodying therein an outer shell having a skirt, and an inner shell having a skirt provided with means adapted to co- 70 operate with complementary means upon the neck of a container in applying a closure to, or removing it from, a container, the bottom edge of the skirt of said inner shell being provided with an outwardly directed flange of a width to engage the skirt of said outer shell, and having at the outer edge thereof a plurality of pendant lugs spaced in relation to each other circumferentially of the skirt, and the bottom edge of the skirt of said outer shell being provided with a continuous, uninterrupted inwardly and upwardly curled portion with its edge in abutting relation to the skirt 75 of the outer shell intermediate said lugs and with the inner face, and in engaging relation with the opposite edges of each of said lugs, and the upper portion thereof in engagement with said flange.

moving it from, a container, the bottom edge of the skirt of said inner shell being provided with an outwardly directed flange of a width to engage the skirt of said outer shell, and having at the outer edge thereof a plurality of pendant lugs 5 spaced in relation to each other circumferentially of the skirt, and the bottom edge of the skirt of said outer shell being provided with a continuous, uninterrupted inwardly and upwardly curled portion with its edge in abutting relation to the skirt 10 of the outer shell intermediate said lugs and with the inner face, and in engaging relation with the opposite edges of each of said lugs, and the upper portion thereof in engagement with said flange.

5. A container closure embodying therein an outer shell having a skirt provided adjacent the top of said shell with a plurality of spaced depressions, and an inner shell having a skirt provided with an enlarged portion adjacent the top thereof and means adapted to co-operate with 20 complementary means upon the neck of a container in applying a closure to, or removing it from, a container, the bottom edge of the skirt of said inner shell being provided with a plurality of pendant lugs spaced in relation to each other 25 circumferentially of the skirt, and the bottom edge of the skirt of said outer shell being inwardly curled to bring its edge in abutting relation to the skirt of the outer shell intermediate said lugs and in engaging relation with the opposite 30 edges of each of said lugs.

6. A container closure embodying therein an outer shell having a skirt provided adjacent the top of said shell with a plurality of spaced depressions, and an inner shell having a skirt provided with an enlarged portion adjacent the top thereof and means adapted to co-operate with complementary means upon the neck of a container in applying a closure to, or removing it from, a container, the bottom edge of the skirt 40 of said inner shell being provided with an outwardly directed flange of a width to engage the skirt of said outer shell, and having at the outer edge thereof a plurality of pendant lugs spaced in relation to each other circumferentially of the skirt, and the bottom edge of the skirt of said outer shell being inwardly curled to bring its edge in abutting relation to the skirt of the outer shell intermediate said lugs and in engaging relation with the opposite edges of each of said lugs, 45 and the upper portion thereof in engagement with said flange.

7. A container closure embodying therein an outer shell having a skirt provided adjacent the top of said shell with a plurality of spaced depressions, and an inner shell having a skirt provided with an enlarged portion adjacent the top thereof and means adapted to co-operate with complementary means upon the neck of a container in applying a closure to, or removing it 55 from, a container, the bottom edge of the skirt of said inner shell being provided with an outwardly directed flange of a width to engage the skirt of said outer shell, and having at the outer edge thereof a plurality of pendant lugs spaced in relation to each other circumferentially of the skirt, and the bottom edge of the skirt of said outer shell being provided with a continuous, uninterrupted inwardly and upwardly curled portion with its edge in abutting relation to the skirt 65 of the outer shell intermediate said lugs and with the inner face, and in engaging relation with the opposite edges of each of said lugs, and the upper portion thereof in engagement with said flange.

CHARLES H. RASMUSSEN. 75
